Primary Examiner—Robin V Webster(74) *Attorney, Agent, or Firm*—Ditthavong Mori & Steiner, P.C.(57) **CLAIM**

The ornamental design for a motionless mixer, as shown.

DESCRIPTION

FIG. 1 is a front side elevational view of a motionless mixer showing my new design;

FIG. 2 is a rear side elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a reference cross-sectional perspective view of the motionless mixer shown in FIGS. 1-6, taken along a line 7—7 of FIG. 1; and,

FIG. 8 is a reference cross-sectional perspective view thereof, taken along a plane including the center axis of the motionless mixer.
